TREATMENT OF PSORIASIS

Mary A. Marcus, New York, N. Y.

Application October 10, 1934, Serial No. 747,662

12 Claims. (Cl. 167—78)

My invention relates to a method for producing a vaccine for treating psoriasis, and to an improved vaccine for treating the said disease.

This application is a continuation in part of 5 my application Serial No. 181,974 filed on April 8, 1927.

One of the objects of my invention is to devise a method whereby the spores of the micro-organism which produce the disease can be efficiently isolated and propagated to produce a pure 10 culture from which a vaccine can be made for treating the said disease.

Another object of my invention is to provide a method whereby the germinated spores having 15 the ordinary form of filamentous micro-organisms can be efficiently isolated to produce a vaccine for the above mentioned purpose.

Another object of my invention is to provide a vaccine for treating the above mentioned disease, it being understood that the claims for the 20 vaccine per se are not limited to any particular method of producing the said vaccine.

Other objects of my invention will be set forth in the following description and drawing which 25 illustrates a preferred embodiment thereof, it being understood that the above general statement of the objects of my invention is intended merely to generally explain the same, and not to limit it in any manner.

The drawing shows a microphotograph of a 30 mono-spore-culture containing the spores 1 and filamentous micro-organisms 2, and all the other important phases indicated by Nos. 3, 4, 5, 6, 7, 8 and 9. This drawing is of the micro-organism 35 enlarged over 400 diameters.

Psoriasis is a skin disease that has been well 40 recognized and has been widespread for a great many years. It manifests itself by the appearance of papules or patches on any part of the skin, the said patches having characteristic white silvery scales. Up to the present time, a great many theories have been advanced to explain the cause of this disease, but no definite and clearly proved theory has heretofore been 45 propounded, and no definite cure has heretofore been proposed.

I have discovered that the cause of psoriasis 50 is a filamentous micro-organism which reproduces by means of spores and which has certain well defined characteristics which will be later explained. I have also discovered that by recovering this in pure culture it can be utilized for treatment in two ways: (A) by direct inoculation of the living micro-organism in the form of solid 55 culture, and (B) by injection of the non-living

micro-organism in vaccine form. Thus both the inoculation on the scarified skin and injections of the produced vaccine have a direct and powerful curative effect.

Hence, whenever I specify the use of vaccine 5 either in the description or in the claims herein, it is understood that I also wish to cover broadly any inoculation with the living micro-organism.

In order to isolate the filamentous micro-organism which produces psoriasis, the following 10 procedure is effective:—

A lesion on the skin of a patient is first washed with 70% alcohol, followed with a wash of 85% and then 95% alcohol to remove or destroy the saprophytes and to thoroughly cleanse the lesion. 15 Some of the surface scales are then immediately transferred to a suitable culture medium such as ordinary agar, glucose agar, maltose agar, Sabouraud's agar, and other ordinary sugar media. Other surface scales are kept for an hour 20 in 60% alcohol and are then inoculated upon the culture medium.

The second batch of scales which are kept for an hour in 60% alcohol are inoculated upon a batch of culture medium which is different from 25 the first batch utilized.

While I wish to have my invention cover the use of scales taken from surface lesions, I have discovered that the use of such scales is not necessary and I do not wish to be limited to the use 30 of such surface scales.

After the surface scales have been removed from a lesion so that the said lesion is substantially free from surface scales, the second level thus secured is again washed with 70% alcohol 35 and then with 95% alcohol and the skin at the second level is then scarified to cause the oozing of serum or lymph. Enough of this serum is taken to inoculate a third batch of culture media and to prepare impression smears both of the 40 serum itself and smears of the mixed serum and the scales taken from the first level.

The exposed surface, which now corresponds to what may be called the third level, is again washed with alcohol as above mentioned; the exposed surface is again irritated; and serum cultures and smears are prepared as above specified in the second stage of my process.

In order to produce the irritation above mentioned, I prefer to use a steel scalpel having a 50 handle about 5 inches long and a point about 2 inches long, one surface of the blade being flat. This scalpel should be kept in a sterilizing solution comprising 95% of phenol and when it is used it is washed in 95% alcohol and is used for 55

scraping only. After each scraping the scalpel is washed with 95% alcohol, the alcohol is removed by sterile cotton, and the scalpel is then put back into the 95% phenol solution.

5 The instrument for removing the serum consists of a shovel-like flattened scoop made of platinum, about two inches long, and connected to a suitable handle. This instrument is sterilized by holding it in a suitable flame and the scoop 10 is thrust upon the scarified surface and pressed forcibly to express the serum or lymph which is then taken up by the scoop and directly inoculated into the culture medium.

15 After each use thereof, the last mentioned instrument, together with the steel handle thereof, is sterilized by holding it in a suitable flame.

10 The above mentioned procedure is important in securing a substantially pure yield of the micro-organism which produces this disease, 20 and I have found that I can secure a yield of over 90%.

25 In addition to securing scales and serum as above mentioned, blood cultures and biopsies can also be taken. For this purpose of taking blood, a suitable surface of the forearm is washed with soap and water, it is then washed with 70% alcohol and then with 95% alcohol, and it is then washed with ether to thoroughly remove the alcohol and any fat. The surface is then washed 30 by a suitable disinfectant, such as a solution of mercurochrome in alcohol. This solution may be prepared by saturating 95% alcohol with mercurochrome and using one part of this solution to 1000 parts by volume of 50% alcohol. The 35 surface is then covered with a sterile dressing for half an hour. After this, the vein is located in the cubital fossa and with a sterile needle and syringe 15 cc. of blood is obtained which is introduced into flasks of maltose agar and kept in 40 incubator until white colonies are seen through the glass (sometimes as long as 6 weeks).

45 As previously mentioned, the reason for carefully sterilizing the tissue prior to taking materials for cultures is to reduce the liability of surface contamination and to secure the causative agent of the disease in as pure a condition as possible.

50 The blood culture obtained is preferably inoculated directly into an Erlenmeyer flask containing a sugar agar-slant. This agar-slant has a surface of substantial area which is inclined to the axis of the flask, so that the micro-organism reproduces freely upon a large exposed surface of the agar and can be detected by means of such 55 surface reproduction, as will be later more fully explained. This micro-organism can be allowed to attain the necessary growth without opening the flask, which lessens the danger of contamination, and it can also be detected by means of its 60 surface growth without opening the flask. Ordinarily in propagating blood cultures in a flask it is necessary to open the flask at fairly frequent intervals to make repeated tests. Of course, each opening of the flask increases the danger of contamination, which is entirely obviated by the 65 procedure above specified.

70 In order to observe whether or not the filamentous causative micro-organisms have been secured, first hanging-drop monospore cultures are studied and thus the different phases of growth and reproduction in which they have been secured are observed. Then permanent smears may be observed microscopically. All smear preparations directly made from the lesions, and also 75 including those made from the cultures to observe

the reproduction of the micro-organisms, are dried in the air, fixed by flame and by a mixture containing equal parts of ether and 95% alcohol. The use of the alcohol-ether mixture is to remove fats. The smears are then stained by any 5 suitable method and I prefer to use Giemsa's method. The Giemsa stain, diluted 60 drops to 100 cc. distilled water, can be directly applied on the smear from 15 to 50 minutes or can be utilized overnight. The Giemsa stain has heretofore been used for staining tissue specimens, in which case the stain was washed out by means of acetone and xylol. But in my method for smears the stain is merely washed out with water.

10 In the same manner smears prepared by impression of the irritated surface of the lesion and from fragments cut from the biopsies obtained from the psoriatic lesions were stained. It is worth noting that the fragments of the psoriatic biopsies first washed in 60% alcohol for an hour 15 and then incubated at 37.5° C. gave both a positive growth and microscopic finding in the smears. That is, the characteristic appearance of the filamentous micro-organism, which I believe to be the causative agent of the disease, was noted 20 culturally and microscopically from both the scrapings as well as the fragments of the biopsies in the annexed drawing including Nos. 1, 2, 3, 25 4, 5, 6, 7, 8 and 9. In the biopsies similar Figures 30 to 1, 5 and 6 as shown in said drawing were observed.

35 When this filamentous micro-organism reproduces under favorable conditions and proper culture media with a pH 6.4 at 37.5° C. it forms a white surface layer upon the culture media, which can be readily observed by the naked eye after sufficient time has elapsed. Of course, the 40 reproductions have variations dependent upon the patient from whom the specimens have been taken and upon other conditions, some of which have not yet been determined. Ordinarily under favorable conditions the said white surface layer which consists mostly of spores can be detected after a lapse of four days and even less as may be noted in the physiological study of the micro- 45 organism.

Physiological study of the "Actinomyces psoriaticum"

50 Generally this micro-organism can be propagated in various culture media of different modified sugars glycerine, either solid agar or bouillon, milk, potato and various synthetic, serum, whole blood and albumin or egg at various temperatures according to the preference of the 55 culture age and behavior, but ranging from below 20° C. to above 40° C. for several days.

60 For descriptive study it is preferable to use body temperature (37.5° C.) and specifying the appearance of the individual colony or the entire culture as it may be necessary within every few hours if possible on the various culture media. It was thus observed that when the micro-organism is grown of glycerine agar or bouillon the colony appears somewhat larger. Even when subcultures are 65 made from glycerine into other sugar media the usual size is increased. In general, under favorable conditions, the colony before fructification, that is, before the white, porcelain, powdery surface takes place, appears round, elevated, uniform 70 in size, gradually assuming a dark green color, penetrating deep into the substratum of the culture medium in from 24 to 48 hours and measures from 3 to 5 microns in diameter, but as soon as fructification occurs the size of the colony in- 75

creases; unless the micro-organism should be in the pleomorphic stage when the colony may become larger without assuming the white surface of spores. More specifically, unless the colony is in a pleomorphic stage, it is usually smaller before the production of the white layer of spores; and larger after such fructification takes place. This white layer consists purely of the spores and the layer under the spores are the filaments which penetrate deep into the substratum of the culture medium. Thus the dark green color of the colony takes place before fructification, that is before the production of the individual spores.

The growth may also differ on the different culture where the degree of the tyrosinase reaction may also vary in the depth and concentration of the dark brown to black color, indicating the moderate, marked or vigorous growth of the micro-organism, Lehman, K. B.: "Über das Vormen von Oxydations fermenten bei Bacterien und Sanum Heren Pflanzen, Arch. Hygiene, 67:99:113.

Stab culture in sugar agar or in gelatine

Most of the strains have grown on the surface as well as in the depth of the medium. The growth appears as a dense beaded dark green streak if before fructification in the first 24 or 36 hours at 37.5° C. or the streak becomes white if this period of incubation exceeds 36 hours. These colonies may also appear as small nodules either on the line of inoculation or on the surface where they are likely to be more dense somewhat spreading into the substratum with a greenish base. The tyrosinase reaction usually takes place within six or ten days of growth varying with the virulence or age of the micro-organism.

Bouillon culture either with the addition of various sugars or with the addition of various chemicals.—The growth also varies with time of incubation as above, but in general the growth appears either at the beginning after 24-36 hours of incubation at 37.5° as solid single or masses of bodies throughout the medium; some float on the surface, others cling to the sides of the tube and still others may sink to the bottom, but the bouillon is always clear unless contamination takes place.

Litmus milk.—Litmus was peptinized within six days at 37.5° C. The reactions appeared to be irregular—some alkaline and others acid.

Egg albumin.—The growth on egg albumin appeared to be very fine, markedly elevated round colonies, which penetrated the substratum of the culture medium. Hydrolysis occasionally occurred as well as the tyrocinase reaction.

Czopack's synthetic culture medium.—This medium occasionally showed very fine shades of chromogenic differences, but the surface colonies also appeared very fine as on the egg albumin, which are not suitable for general description. Solid culture of carbohydrates were therefore necessary for the study of general description.

Details of the growth observed on glucose agar or double or triple sugar and glycerine are similar to those described under solid and bouillon culture media.

More details will be described under the morphological study as well as under the treatment by the inculcation of the living micro-organism obtained from the surface growth of solid media and inoculated into the scarified sound skin of the patient and also under the preparation of specific psoriasis vaccine which can be prepared either from solid or bouillon culture media upon

which the micro-organism has been grown and obtained in pure culture after it has been subcultured a number of times.

The following studies are given as an explanation and description of the specific organism causing psoriasis which is found and the methods by which it may be applied to treat the disease.

*Morphology of *Actinomyces psoriaticum**

Morphologically the "*Actinomyces psoriaticum*" has points of resemblance to *Actinomyces VIII*, described by Drechsler (Morphology of the Genus *Actinomyces*, The Chemical Gazette, Nos. 1 and 2, January and February, 1919) and culturally resembles *Actinomyces V* Stamm 39, described by Lieske (Morphologie und Biologie des Strahlenpilze, pages 279 and 293, Heidelberg, October, 1920, Botanische Institut) and as noted in the drawing. The characteristics which retain the identity of "*Actinomyces psoriaticum*" will be pointed out below:

Although other *Actinomyces* of different sources have been studied along with "*Actinomyces psoriaticum*" only the latter showed characteristics that may be essential in order to differentiate it from the other *Actinomyces* of other sources than psoriasis.

Five strains of the "*Actinomyces psoriaticum*" monospore cultures have been studied in the hanging-drop-wet-chamber preparation. Under suitable conditions in glucose agar the micro-organism from all the five strains grew essentially in the same manner in the hanging-drop cultures. If the water in the bottom was sufficient to prevent the hanging-drop from drying, and the cultures were kept continuously in the incubator, there occurred a branching filamentous growth in two days. Gradually, more or less, erect fructification developed along the distal portion; the fertile hyphae at times appeared to be attached to the axial filaments in a diffuse system. In the course of about a week or more the swellings in the axial filaments at the base of the sporogenous branches indicate the site of origin, and the germination of some separated single spores or clusters of spores is also one of the characteristics of identification. Besides those characteristics of the grouping of the spores, the size and shape of the spores are also points of differential classification:—The spores are ellipsoidal showing a definite central body which specifies to call the spores uninucleated, measuring 0.5 to 1.3 microns in diameter. If about 1% phosphate is added to the culture media, there develop close sinistral spirals consisting of 2-4 turns, measuring 1.5 to 2.5 microns in diameter; also if carefully studied, characteristic cork-screw bodies are observed which consist of 2-4 loops and 1-3 knobs, as shown at 6 in the drawing.

It is thus noted that the limited and definite grouping, size and shape of the spores; the limited number of spirals (2-4); the limited number of loops (2-4) as well as the limited number of knobs (1-3) are the characteristic points of differential classification and therefore these points retain the identity of the "*Actinomyces psoriaticum*".

The *Actinomyces* described by Drechsler show a greater number of the spirals, cork-screw bodies and knobs than the "*Actinomyces psoriaticum*" while the *Actinomyces* described by Lieske did not show any of these characteristics in his report.

The parts illustrated in the drawing are identified as follows:

1. A single spore.
2. Filaments of a germinated spore.
- 5 3. A sporogenous branch with terminal spirals.
4. A germinating spore with germ-tube.
- 5 Aerial mycelium hooked over with the spiral hyphae of another branch.
- 10 6. Spirals and cork-screw bodies showing definite loops in groups of three. The same number (three) of loops was observed in another culture and in a section of a biopsy taken from a psoriasis lesion which also showed same number of three loops.
- 15 7. Germinating spores with fructification developed in successive sequence with chains and single spores with germ-tube.
8. Fertile aerial mycelium showing spore indicating origin of sporogenous short branch 20 of mycelium consisting of immature spores.
9. Aerial germinating spore with two germ-tubes, originating from mycelia including immature spores.

25 *Therapeutic properties of "Actinomyces psoriaticum" detected*

During the experiment in carrying out Koch's postulate on psoriatics and non-psoriatics as well as animals (including monkeys and rabbits) by 30 direct inoculation of the living micro-organisms obtained from the surface growth of solid culture media at different stages of the *Actinomyces psoriaticum*, it was noted that the pre-existing lesions in the psoriatics either completely or partially cleared up after about eight series of inoculations into the scarified skin were made during 35 two months.

With further persistent effort, it was noted that these inoculations made into scarified skin in 40 quiescent psoriasis cases, the active stage took place after six series of inoculations with the living micro-organism into the scarified skin. The first series was started with three scarification inoculations and gradually increased with one 45 additional scarification at a time, until ten such inoculations were made at the last series. This usually gave rise to an active stage at which time the clearing of the original lesions were observed.

Hence I believe that this micro-organism possessed therapeutic properties and a vaccine therapy as well as the scarification-inoculation treatment was tried with successful results.

These inoculations were made purely from the surface growth of the micro-organism from solid 55 media which was readily removed from the culture medium. These spores do not have a shape which distinguishes them from the genus *Actinomyces*.

Directly underneath this easily removed surface 60 layer, a filamentous structure is found which has penetrated and is closely associated with the culture medium, so that it is not possible to remove this filamentous structure without taking along some of the culture medium simultaneously.

65 The surface layer of the culture, which comprises both the filamentous micro-organism and the living spores and filaments, can be used directly by scarification and then by gently rubbing in the culture medium so that it is absorbed by 70 the blood of the patient. This medium should be applied by means of the platinum scoop previously mentioned.

75 However, as this requires very tedious and careful manipulation, although it is therapeutically effective, I prefer to use the vaccine later men-

tioned, although direct application of the living culture is often of great value in quickly producing the active stage of the disease in a patient, so that the vaccine is then more effective. I have discovered that when psoriasis lesions are in the 5 active stage the vaccine treatment is more effective. I have further discovered that the direct inoculation of the living organism isolated from psoriasis into quiescent psoriatics produces more active psoriasis lesions on sound skin. This more 10 active form lends itself to the vaccine treatment more readily than the quiescent form.

In order to prepare the vaccine, the subcultures are prepared upon the slant-agar surface from the initial growth previously mentioned (preferably in an Erlenmeyer flask) and they are allowed to germinate for only about two days at 37° C. and before fructification has taken place with the formation of the white surface layer previously mentioned. 15

The surface of the agar culture now contains the colonies in filamentous and germinating form and these cling so firmly to the said surface of the agar that the surface portion of the agar must be cut out in order to remove the germinating 20 colonies. 25

The culture thus secured is collected in previously sterilized glass bottles which contain sterilized glass beads and a normal saline solution (NaCl—0.85%) intermixed with a .3% phenol 30 solution.

The cultures from several patients are preferably intermixed in one of these bottles so as to produce a polyvalent vaccine. I wish to state at this point that even following all the precautions 35 above mentioned, it is not always possible to secure a culture from a patient, and that the ease of obtaining cultures from various patients differs with individual characteristics.

A vaccine can also be produced from the culture containing both the spores and the filaments of the micro-organisms, but is less reliable, and hence I prefer to use the first mentioned vaccine. 40

The several strains of culture are now vigorously shaken, preferably by machine, from two 45 to four days and even more, until the said suspension is homogenous.

The several strains of the culture are now vigorously shaken, by special machine, from twenty-four to forty-eight hours and even longer, until 50 the said suspension is homogenous and is free from clots, so that a drop thereof, free from clots, can be readily taken up by the finest hypodermic needle.

The consistency of the vaccine is now determined by comparing the viscosity of a standard vaccine, such as the *Staphylococcus* vaccine, having 55 10,000 per cc.

The suspension is now made sterile either by heating it at a temperature of 60° C. for three 60 hours, followed by an addition of 0.5% phenol; or the phenol and heat is not used at all, but instead the saline (0.85%) used for the suspension is first treated with 1:5000 "merthiolate" and then when the micro-organism is suspended and shaken for a sufficient period of time (24-48 hours) the suspension is incubated for three days at 37.5° C. and then tested for sterility. A number of other chemicals have been successfully tried in effecting sterility without the heating of the 65 suspension. Among these chemicals were included phenol and creosote, etc., but it was found that the "merthiolate" is most efficient as there it causes no breaking down of the constituents into protein. And furthermore, after sterility is ef- 70 75

fected with the 1:5000 dilution of the "merthiolate" it can be then further diluted as high as 1:60,000. The latter principle of sterilizing the suspensions was also found effective in sterilizing 5 the various extracts and filtrates that are prepared from this micro-organism—"Actinomyces psoriaticum". These extracts include saline, ether and alcohol as given in the preparation of the extract vaccine for the treatment and testing 10 intradermally in dermatoses.

The above extracts or suspensions can be prepared either from the propagated micro-organism on the various agar-agar culture media, or in various modified bouillons, including all the combinations of sugars, blood, blood serum and glycerine or the synthetic media which need not have an exposed surface. At the end of 38 or 15 48 hours appear the characteristic round, dense beaded streaks (or lines of small nodules) along 20 the line of inoculation. In bouillon these colonies may float on the surface or cling to the sides of the tube. If the growth is prolonged the colonies become white masses or individual groups of 25 bodies or both on the surface and throughout the medium. For the purpose of preparing the suspensions or the extracts it is necessary to remove the growth of the micro-organism either from the solid culture media or from the bouillon before white growth or the individual spores are 30 formed which can be seen by microscopic examination not before the 36 hours of growth. If the growth is thus prepared in bouillon culture media it should be removed either by syphoning off the bouillon or by filtering it off, and retaining 35 the micro-organism on the filter, which is then used either for the suspension or for extracts, as well as for microscopic characteristics in order to detect and eliminate the spores.

It is absolutely necessary substantially either 40 to inhibit the formation of the spores, which is preferable, or to eliminate spores in the production of the vaccine; because the presence of spores has been found to produce certain undesirable incidental effects, such as the production 45 of abscesses or the like.

Thus the extract vaccine which is an extract and a filtrate of the micro-organism "Actinomyces psoriaticum" is preferable for the therapeutic purpose.

50 *Method of preparing psoriasis extract*

I have also succeeded in preparing an extract of psoriasis vaccine. This extract is obtained from the "Actinomyces psoriaticum". The 55 above suspension prepared for the "specific psoriasis vaccine" is also applied for the preparation of the extract, but without shaking. Thus, the suspension of the spore-free filamentous colonies obtained from the growth of the "Actinomyces psoriaticum" in the vehicle—0.85% saline containing 2.5% phenol—is kept in the incubator at 37.5° C. for 48 hours, then tested for sterility and without shaking is subjected to extraction with sterile 0.85% saline at intervals of 60 two weeks, in a course of eight weeks, and then subjected to the Berkefeld filter. This extract is thus diluted to the extent where it reaches to retain only 0.5% phenol, but further dilutions may be necessary when applied for testing.

70 This extract is efficient either for treatment or for testing, subcutaneously and intradermally, respectively. The purpose of testing with this extract is to determine the degree of susceptibility or the degree of the immunity established during the course of treatment either with the

"specific psoriasis vaccine" or with the extract, respectively, or both used alternatively.

I claim:

1. In preparing a polyvalent vaccine for the treatment of psoriasis the steps which consist in 5 treating papules of said disease with a sterilizing medium, securing from said papules a filamentous micro-organism herein referred to as *Actinomyces psoriaticum*, said micro-organism being capable of reproducing in culture media 10 having a pH of 6.4 at temperatures between 20 and 40° C. and forming round dark green colonies measuring from 3 to 5 microns in diameter, said colonies increasing in size and acquiring a white 15 powdery surface when fructification occurs, said micro-organisms having ellipsoidal spores measuring from .5 to 1.3 microns in diameter, said micro-organisms also containing bodies having close sinistral spirals of 2-4 turns and corkscrew-shaped bodies having 2-4 loops and 1-3 knobs 20 when 1% phosphate is added to the medium containing said micro-organism, propagating said micro-organism in a culture medium, preparing sub-cultures therefrom, separating the spore-free filamentous germinating form of the said 25 micro-organism from the subculture medium, intermixing said spore-free filamentous germinating form of the said micro-organism with other strains of the same form of said micro-organism from other sources, suspending these mixed 30 strains in a liquid vehicle, homogenizing the suspension, and sterilizing the said suspension.

2. In preparing a vaccine for treatment of psoriasis, the steps which consist in treating infected papules of said disease with a sterilizing 35 medium, securing from said papules a filamentous micro-organism herein referred to as *Actinomyces psoriaticum*, said micro-organism being capable of reproducing in culture media 40 having a pH of 6.4 at temperatures between 20 and 40° C. and forming round dark green colonies measuring from 3 to 5 microns in diameter, said colonies increasing in size and acquiring a white 45 powdery surface when fructification occurs, said micro-organisms having ellipsoidal spores measuring from .5 to 1.3 microns in diameter, said micro-organisms also containing bodies having close sinistral spirals of 2-4 turns and corkscrew shaped bodies having 2-4 loops and 1-3 knobs when 1% phosphate is added to the medium containing said micro-organism, propagating said 50 micro-organism in a culture medium, preparing sub-cultures therefrom, separating the spore-free filamentous germinating form of the said micro-organism from the sub-culture medium, suspending this micro-organism in a liquid vehicle, homogenizing the suspension and sterilizing 55 the said suspension.

3. In preparing a polyvalent vaccine for the treatment of psoriasis, the steps which consists 60 in treating infected papules of said disease with a sterilizing medium, securing from biopsies of said papules of filamentous microorganism herein referred to as *Actinomyces psoriaticum*, said micro-organism being capable of reproducing in culture 65 media having a pH of 6.4 at temperatures between 20 and 40° C. and forming round dark green colonies measuring from 3 to 5 microns in diameter, said colonies increasing in size and acquiring a white powdery surface when fructification occurs, said micro-organisms having ellipsoidal spores measuring from .5 to 1.3 microns in diameter, said micro-organisms also containing bodies having close sinistral spirals of 2-4 turns and corkscrew shaped bodies having 2-4 70 turns and corkscrew shaped bodies having 2-4 75

loops and 1-3 knobs when 1% phosphate is added to the medium containing said micro-organism, propagating said micro-organism in a culture medium, preparing subcultures therefrom, separating the spore-free filamentous germinating form of the said micro-organism from the subculture medium, intermixing said spore-free filamentous germinating form of the said micro-organism with other strains of the same form of 5 said micro-organism from other sources, suspending these mixed strains in a liquid vehicle, homogenizing the suspension, and sterilizing the said suspension.

4. In preparing a polyvalent vaccine for the 15 treatment of psoriasis, the steps which consist in treating infected papules of said disease with a sterilizing medium, securing from said papules a filamentous micro-organism herein referred to as *Actinomyces psoriaticum*, said micro-organism

20 being capable of reproducing in culture media having a pH of 6.4 at temperatures between 20 and 40° C. and forming round dark green colonies measuring from 3 to 5 microns in diameter, said colonies increasing in size and acquiring a white 25 powdery surface when fructification occurs, said micro-organisms having ellipsoidal spores measuring from .5 to 1.3 microns in diameter, said micro-organisms also containing bodies having close sinistral spirals of 2-4 turns and cork- 30 screw shaped bodies having 2-4 loops and 1-3 knobs when 1% phosphate is added to the medium containing said micro-organism, propagating said micro-organism in a culture medium, preparing sub-cultures therefrom, separating the 35 spore-free filamentous germinating form of the said micro-organism from the sub-culture medium, intermixing said spore-free filamentous germinating form of said micro-organism with other strains of the same form of said micro- 40 organism, suspending these mixed strains in a liquid vehicle, adding "merthiolate" to said suspension, incubating to kill said micro-organism and homogenizing said suspension.

5. In preparing an agent for the treatment of 45 psoriasis those steps which consist in treating infected papules of said disease with a sterilizing medium, securing from said papules a filamentous micro-organism herein referred to as *Actinomyces psoriaticum*, said micro-organism being capable 50 of reproducing in culture media having a pH of 6.4 at temperatures between 20 and 40° C. and forming round dark green colonies measuring from 3 to 5 microns in diameter, said colonies increasing in size and acquiring a white powdery 55 surface when fructification occurs, said micro-organisms having ellipsoidal spores measuring from .5 to 1.3 microns in diameter, said micro-organisms also containing bodies having close sinistral spirals of 2-4 turns and corkscrew shaped 60 bodies having 2-4 loops and 1-3 knobs when 1% phosphate is added to the medium containing said micro-organism, propagating said micro-organism in a culture medium having an exposed 65 surface, separating from said culture medium the spores found adjacent to said exposed surface and separating from said culture medium the exposed 70 surface portions thereof containing spores and filamentous micro-organism.

6. In preparing an agent for the treatment of 70 psoriasis those steps which consist in treating infected papules of said disease with a sterilizing medium, securing from the various levels of said papules a filamentous micro-organism herein referred to as *Actinomyces psoriaticum*, said 75 micro-organism being capable of reproducing in

culture media having a pH of 6.4 at temperatures between 20 and 40° C. and forming round dark green colonies measuring from 3 to 5 microns in diameter, said colonies increasing in size and acquiring a white powdery surface when fructification occurs, said micro-organisms having ellipsoidal spores measuring from .5 to 1.3 microns in diameter, said micro-organisms also containing bodies having close sinistral spirals of 2-4 turns and corkscrew shaped bodies having 2-4 loops and 1-3 knobs when 1% phosphate is added to the medium containing said micro-organism, propagating said micro-organism in a culture medium having an exposed surface, separating from said culture medium the spores found adjacent to said exposed surface and separating from said culture medium the exposed surface portions thereof containing spores and filamentous micro-organism.

7. In preparing an agent for the treatment of 20 psoriasis those steps which consist in treating infected papules of said disease with a sterilizing medium, securing from the biopsies of said papules a filamentous micro-organism herein referred to as *Actinomyces psoriaticum*, said micro-organism 25 being capable of reproducing in culture media having a pH of 6.4 at temperatures between 20 and 40° C. and forming round dark green colonies measuring from 3 to 5 microns in diameter, said colonies increasing in size and acquiring a white 30 powdery surface when fructification occurs, said micro-organisms having ellipsoidal spores measuring from .5 to 1.3 microns in diameter, said micro-organisms also containing bodies having close sinistral spirals of 2-4 turns and corkscrew 35 shaped bodies having 2-4 loops and 1-3 knobs when 1% phosphate is added to the medium containing said micro-organism, propagating said micro-organism in a culture medium having an exposed surface, separating from said culture medium the spores found adjacent to said exposed surface and separating from said culture medium the exposed surface portions thereof containing 40 spores and filamentous micro-organism.

8. A sterile vaccine for the treatment of 45 psoriasis comprising a suspension of a spore-free substantially filamentous micro-organism herein referred to as *Actinomyces psoriaticum*, said micro-organism being capable of reproducing in culture media having a pH of 6.4 at temperatures between 20 and 40° C. and forming round 50 dark green colonies measuring from 3 to 5 microns in diameter, said colonies increasing in size and acquiring a white powdery surface when fructification occurs, said micro-organisms having ellipsoidal spores measuring from .5 to 1.3 microns in diameter, said micro-organisms also containing bodies having close sinistral spirals of 2-4 turns and corkscrew shaped bodies having 55 2-4 loops and 1-3 knobs when 1% phosphate is 60 added to the medium containing said micro-organism, said suspensions being prepared according to the steps consisting of treating papules of said disease with a sterilizing medium, securing said micro-organism from said papules, 65 propagating said micro-organism, preparing a sub-culture therefrom, separating the spore free filamentous germinating form of the said micro-organism from the subculture medium, suspending said micro-organism obtained from the subculture in a liquid vehicle, homogenizing the suspension and sterilizing the said suspension.

9. A sterile polyvalent vaccine for the treatment of psoriasis comprising a suspension of a spore-free substantially filamentous micro-or- 70

ganism herein referred to as *Actinomyces psoriaticum*, said micro-organism being capable of reproducing in culture media having a pH of 6.4 at temperatures between 20 and 40° C. and forming round dark green colonies measuring from 3 to 5 microns in diameter, said colonies increasing in size and acquiring a white powdery surface when fructification occurs, said micro-organisms having ellipsoidal spores measuring from .5 to 1.3 microns in diameter, said micro-organisms also containing bodies having close sinistral spirals of 2-4 turns and corkscrew shaped bodies having 2-4 loops and 1-3 knobs when 1% phosphate is added to the medium containing said micro-organisms, said suspension being prepared according to the steps consisting of treating papules of said disease with a sterilizing medium, securing said micro-organism from said papules, propagating said micro-organism, preparing a sub-culture therefrom, separating the spore-free filamentous germinating form of the said micro-organism from the sub-culture medium, intermixing said micro-organism obtained from the sub-culture with other strains obtained in the same manner, suspending these mixed strains in a liquid vehicle, homogenizing the suspension and sterilizing the said suspension.

10. A sterile vaccine for the treatment of psoriasis comprising a polyvalent extract and filtrate of a spore-free substantially filamentous micro-organism herein referred to as *Actinomyces psoriaticum*, said micro-organism being capable of reproducing in culture media having a pH of 6.4 at temperatures between 20 and 40° C. and forming round dark green colonies measuring from 3 to 5 microns in diameter, said colonies increasing in size and acquiring a white powdery surface when fructification occurs, said micro-organisms having ellipsoidal spores measuring from .5 to 1.3 microns in diameter, said micro-organisms also containing bodies having close sinistral spirals of 2-4 turns and corkscrew shaped bodies having 2-4 loops and 1-3 knobs when 1% phosphate is added to the medium containing said micro-organism, said extract being prepared according to the steps consisting of treating papules of said disease with a sterilizing medium, securing said micro-organism from said papules, propagating said micro-organism, preparing a sub-culture therefrom, separating the spore-free filamentous germinating form of the said micro-organism from the sub-culture medium, suspending said micro-organism obtained from the sub-culture in a liquid vehicle, sterilizing the said suspension without shaking it, and preparing an extract and filtrate therefrom.

11. In preparing a vaccine for the treatment of psoriasis, the steps which consist in sterilizing a portion of sound skin, obtaining a sample of the psoriatic patient's blood through the sterile portion of the said skin, securing from said blood a filamentous micro-organism herein referred to as *Actinomyces psoriaticum*, said micro-organism being capable of reproducing in culture media having a pH of 6.4 at temperatures between 20 and 40° C. and forming round dark green colonies measuring from 3 to 5 microns in diameter, said colonies increasing in size and acquiring a white powdery surface when fructification occurs, said micro-organisms having ellipsoidal spores measuring from .5 to 1.3 microns in diameter, said micro-organisms also containing bodies having close sinistral spirals of 2-4 turns and corkscrew shaped bodies having 2-4 loops and 1-3 knobs when 1% phosphate is added to the medium containing said micro-organism, propagating said micro-organism in a culture medium, preparing sub-cultures therefrom, separating the spore-free filamentous germinating form of the said micro-organism from the sub-culture medium, intermixing said spore-free filamentous germinating form of the said micro-organism from other sources, suspending these mixed strains in a liquid vehicle, homogenizing the suspension, and sterilizing the said suspension.

12. A sterile vaccine for the treatment of psoriasis comprising a suspension of the spore-free substantially filamentous micro-organism herein referred to as *Actinomyces psoriaticum*, said micro-organism being capable of reproducing in culture media having a pH of 6.4 at temperatures between 20 and 40° C. and forming round dark green colonies measuring from 3 to 5 microns in diameter, said colonies increasing in size and acquiring a white powdery surface when fructification occurs, said micro-organisms having ellipsoidal spores measuring from .5 to 1.3 microns in diameter, said micro-organisms also containing bodies having close sinistral spirals of 2-4 turns and corkscrew shaped bodies having 2-4 loops and 1-3 knobs when 1% phosphate is added to the medium containing said micro-organism, said suspension being prepared according to the steps consisting in sterilizing a portion of the sound skin, obtaining a sample of the psoriatic patient's blood through the said skin, propagating the said micro-organism contained in said blood in a culture medium, preparing sub-cultures therefrom, separating the spore-free filamentous germinating form of the said micro-organism from the sub-culture medium, suspending said micro-organism obtained from the sub-culture in a liquid vehicle, homogenizing the suspension and sterilizing the said suspension.

MARY A. MARCUS.
